VISOR FOR AUTOMOBILE HEAD LAMPS

David Patis, Chicago, Ill.

Application March 28, 1955, Serial No. 35,239

Term of patent 3½ years

(Cl. D48—32)

Fig. 1 is a perspective view of a visor for automobile head lamps, showing my new design.

Fig. 2 is a front elevational view of the same.

Fig. 3 is a top plan view of the same.

Fig. 4 is a side elevational view of the same.

I claim:

The ornamental design for a visor for automobile head lamps, substantially as shown.
